UNITED STATES PATENT OFFICE

165,036

MERCHANDISE DISPLAY CASE

Franz Wagner, Chicago, Ill., assignor to Eko Products Company, Chicago, Ill., a corporation of Illinois

Application March 28, 1949, Serial No. 1,669

Term of patent 14 years

(Cl. D80—11)

To all whom it may concern:

Be it known that I, Franz Wagner, a citizen of the United States, residing at Chicago, in the county of Cook, State of Illinois, have invented a new, original, and ornamental Design for a Merchandise Display Case, of which the following is a specification, reference being had to the accompanying drawing, forming part thereof.

Fig. 1 is a front perspective view of a merchandise display case, showing my new design.

Fig. 2 is an enlarged vertical sectional view taken on line 2—2 of Fig. 1, the bottom of the case being omitted for convenience of illustration.

The perforations on the top of the display case are uniform but are shown fragmentary for convenience of illustration.

The dominant feature of the design resides in the portion shown in full lines.

I claim:

The ornamental design for a merchandise display case, as shown and described.

FRANZ WAGNER.
